UNITED STATES PATENT OFFICE.

WILLIAM WINKELMAN, OF LOS ANGELES, CALIFORNIA.

BLAST FURNACE.

1,402,464.

Specification of Letters Patent. Patented Jan. 3, 1922.

Application filed February 10, 1920. Serial No. 357,678.

To all whom it may concern:

Be it known that I, WILLIAM WINKELMAN, a citizen of the United States, residing at Los Angeles, in the county of Los Angeles, and 5 State of California, have invented a new and useful Blast Furnace, of which the following is a specification.

My invention relates to blast furnaces, being more particularly a blast furnace in 10 which oil or gas is used as fuel.

The principal object of my invention is to produce a blast furnace of the character described, of simple form and construction, which may be efficiently operated for producing 15 the desired results.

Other objects and advantages will be made evident hereinafter.

Referring to the drawings, which are for 20 illustrative purposes only,

Fig. 1 is a vertical sectional view of a furnace embodying a form of my invention.

Fig. 2 is a vertical sectional view on line 2—2, Fig. 1 of the lower portion of the furnace.

Fig. 3 is a sectional plan view on line 3—3, Fig. 2.

Fig. 4 is an enlarged vertical sectional view through one of the burners.

The furnace 11 is provided with a vertically arranged chamber 12 having formed in the inner walls thereof an upper bosh 13 and a lower bosh 14, that portion of the chamber at the upper bosh and above being the reducing or carburizing zone, and that 35

portion of the chamber at the lower bosh and below, the melting chamber. 15 designates a series of arches for supporting the ore in the furnace, the lower portion of the furnace below the arches designated at 16 being the pit 40 or crucible to receive the melted ore, this crucible having a hearth at its lower part provided with an outlet 17 through which the melted ore may be discharged, and also an opening 18 through which the slag may be 45 removed.

Each of the openings 17 and 18 are formed in castings 19 and 20 respectively, which castings are formed with water jackets 21 into which water is introduced and removed through pipes 22 and 23.

Directly below the upper bosh 13 is a plurality of burners or tuyeres 25, and directly below the lower bosh 14 is a plurality of burners or tuyeres 26. Each of these burners is surrounded by a water jacket 28 set into 55 the walls of the furnace, each water jacket

having an inlet pipe 29 and an outlet pipe 30. Each burner has a fuel passage 32 and a fuel outlet 33, an oil or gas supply pipe 34 extending into the fuel passage.

Each burner is provided with an extension 60 35 which extends inwardly from the walls of the furnace over the outlet 33, and directly below the fuel passage 32 in an upwardly directed air passage 37 having an air outlet 38 directly below the fuel outlet 33. The 65 burners are each hollow, having a water chamber 40 which extends into the extension 35, water being supplied to such chamber by means of a pipe 41 and removed from such chamber by means of the water outlet pipe 70 42. The air passage extends outwardly and downwardly as indicated at 43 and is provided with a peep hole 44 having a suitable plug 45.

These burners are preferably made elliptical in shape, the water jacket surrounding the burners being similarly shaped. In operation the chamber above the arches is filled with ore. During the operation of the burners the melting of the ore is carried out in the 75 following manner. The upper burners or tuyeres are so regulated that an incomplete combustion is produced in the body of the ore about the burners and above the same thereby releasing into the body of ore in the reducing 80 zone carbon monoxide which reduces the ore in the upper part or reducing zone of the furnace. At the same time the lower burners 26 are arranged to produce a combustion in the body of ore in the melting zone sufficient to 85 reduce the ore to a melted state therein, the melted material falling into the pit or crucible 16 from which it may be removed through the opening 17, the slag being removed through the opening 18. The extensions 35 90 on the burners prevent the slag from clogging the mouth of the burner so that the flame from the burners may be driven well into the body of the ore.

It is understood that the heat in the melting zone is controlled by the introduction of air through the air passages 37 and that the flame may be regulated thereby into a neutralizing, oxidizing or reducing flame.

What I claim is:

1. A blast furnace comprising a vertically arranged chamber having a reducing and carburizing zone in the upper portion thereof and a melting zone below the reducing zone, means for incompletely burning gase- 110

ous fuel in the chamber in the lower part of the reducing zone to furnish carbon monoxide to the ore in the reducing zone, means for completely burning gaseous fuel in the melting zone, a crucible in the bottom of said chamber and a series of arches above said crucible.

5 2. A blast furnace comprising a vertically arranged chamber having a reducing and carburizing zone in the upper portion thereof and a melting zone below the reducing zone, a gaseous fuel burner arranged to furnish carbon monoxide to the ore in the reducing zone, a gaseous fuel burner arranged 10 to melt the ore in the melting zone, a crucible in the bottom of said chamber and a series of arches above said crucible.

15 3. A blast furnace comprising a vertically arranged chamber having a reducing and carburizing zone in the upper portion thereof and a melting zone below the reducing zone, a gaseous fuel burner arranged to furnish carbon monoxide to the ore in the reducing zone, and a gaseous fuel burner arranged 20 to melt the ore in the melting zone, each of said burners having a portion extending inwardly from the walls of the furnace overhanging the fuel outlet of the burner.

25 4. A blast furnace comprising a vertically arranged chamber having a reducing and carburizing zone in the upper portion thereof and a melting zone below the reducing zone, a gaseous fuel burner arranged to 30 furnish carbon monoxide to the ore in the reducing zone, a gaseous fuel burner arranged to melt the ore in the melting zone, said chamber having two boshes formed in the walls thereof one above each set of

burners, a crucible in the bottom of said 40 chamber and a series of arches above said crucible.

5 5. A blast furnace having a plurality of gaseous fuel burners arranged in the walls thereof, each of said burners having a fuel 45 outlet and a separate air outlet directly below the fuel outlet arranged to direct the flame upwardly.

6. A blast furnace having a plurality of gaseous fuel burners arranged in the walls 50 thereof, each of said burners having a fuel outlet and a separate air outlet arranged below the fuel outlet, and an extension formed on each burner extending into the furnace over the fuel outlet.

55 7. A blast furnace having a plurality of water jackets in the walls thereof and a removable fuel burner in each jacket, said burners each having a fuel passage terminating in a fuel outlet and an air outlet 60 below the fuel outlet, an extension on each burner extending into the furnace chamber over the fuel outlet, and means for introducing air into the fuel passage.

8. A blast furnace having a plurality of gaseous fuel burners arranged in the walls thereof, each of said burners having a fuel 65 outlet and a separate air outlet arranged below the fuel outlet, a hollow extension formed on each burner extending into the 70 furnace above the fuel outlet of the burner, and means passing a current of water through said extension.

In testimony whereof, I have hereunto set my hand at Los Angeles, California, 75 this 2nd day of February, 1920.

WILLIAM WINKELMAN.
